UNITED STATES PATENT OFFICE

GEORGE E. A. HALLETT, OF DETROIT, MICHIGAN, ASSIGNOR TO GENERAL MOTORS RESEARCH CORPORATION, OF DETROIT, MICHIGAN, A CORPORATION OF DELAWARE

HYDRAULIC VALVE OPERATING MECHANISM

Application filed April 4, 1927. Serial No. 180,915.

This invention relates to hydraulic mechanism for operating the valves of internal combustion engines and similar devices, in which a body of fluid is interposed between an operating part and an operated part to transmit movement. In apparatus of this character one of the chief obstacles in the way of successful operation is the fact that air becomes mixed with the oil or other fluid, forming an emulsion which it is very difficult to remove. According to this invention the oil supplied to replenish the fluid body to take care of losses from leakage and other causes is subjected to an operation in which air is effectively and positively removed prior to the admission of the oil to the system. This is preferably accomplished by the employment of centrifugal action, as a result of which the air bubbles owing to their lighter weight collect in the center of the separator where provision is made for leading them together with some of the oil either to the bearings or other parts to be lubricated or to the crank case. With this arrangement may be combined a settling tank, the oil used to supply the hydraulic system being drawn from adjacent the lower portion of the tank and the bottom of the tank serving for the collection of sediment.

Another feature of my invention consists in improvements in the operating piston by which force is transmitted to the body of fluid for operation of the valve. To avoid subjecting the piston to side thrusts as a result of cam action which would cause wear in the guides, giving rise to leakage, I interpose a reciprocating part between the cam shaft and the piston. This may be in the form of a plunger suitably guided and in alinement with the piston. For convenience in manufacture the guide for the plunger may be formed in the crank case and the plunger may be a relatively loose fit in the guide. The piston, on the contrary, must fit its guide very closely, and the latter is conveniently formed separately from the crank case and secured thereto in alinement with the first named guide.

Oil is preferably fed to the system through ports formed in the piston and its guide,

these ports alining during portions of the stroke when the valve is not being actuated.

Other features of the invention will be disclosed in the following description.

In the drawings, Figure 1 is a diagrammatic view showing in partial vertical section an automobile engine to which my invention is shown applied. 55

Figure 2 is an enlarged detail view of portions of the structure shown in Figure 1. 60

Figure 3 is a section on line 3—3 of Figure 2.

Figure 4 is a diagrammatic view, similar to Figure 1, showing my invention applied in a system of somewhat different type. 65

In Figures 1 and 2, I have illustrated an internal combustion engine of the overhead valve type provided with the usual crank case 2, crank shaft 4, cylinders 6 and pistons 8. I have indicated at 10 one of the overhead valves which is held upon its seat by spring 12 in the usual manner. 14 indicates the conventional cam shaft. 70

Above the valve 10 I have provided a plunger 16 guided in bore 18 communicating with chamber 20. At the other side of the engine the chamber 20 is connected by conduit 22 to cylinder 26 in which reciprocates piston 28, yieldingly urged in a downward direction by spring 30. Cylinder 26 is preferably of hardened steel and the piston 28 is a close fit in the cylinder to prevent leakage of oil or other fluid which fills the chamber 20, conduit 22 and cylinder 26. Cylinder 26 is in alinement with bore 32 formed in the crank case and in which is fitted plunger 24 engaging the cam shaft 14. It will now be understood that with the system filled with fluid, rotation of the cam shaft will cause plunger 24 and piston 28 to move upwardly in opposition to spring 30 displacing the fluid in the system and causing plunger 16 to be forced downwardly opening the valve 10. 80 85 90

I have provided the following means to replenish the fluid in the system to insure effective operation: at 38 I have shown the usual engine driven oil pump which may supply oil to certain of the bearings through conduit 40, while conduit 41 leads to the usual dash pressure gage. Pump 38 likewise sup- 100

plies oil through tube 42 to the combined separator and settling tank 44. Tube 42 may be provided with check valve 43 to prevent return of oil to the crankcase. It will be noted that the top of the tank is of conical form and tube 42 communicates tangentially with the tank just below the control portion as shown in Figure 3. Conduit 46 likewise extending tangentially from the tank leads oil from the bottom of the tank to passage 48 in cylinder 26. Piston 28 is provided with a peripheral groove 49 from which a plurality of passages 50 lead to the interior of the piston. At the upper end of the piston is provided an upwardly opening check valve 51 yieldingly held upon its seat by spring 52. At the upper end of tank 44 is arranged a pressure relief valve 53 controlling the passage of oil from the tank into conduit 54 which may have a branch 56 leading to certain of the engine bearings or other parts requiring lubrication. Conduit 54 discharges into crank case 2 and at some convenient point beyond the branch 56 is provided with a second pressure relief valve 58.

The operation of the system for replenishing the liquid column is as follows: A portion of the output of the pump 38 passes through conduit 42 to tank 44 in which it performs a whirling motion as a result of its tangential connection to the tank. This causes air bubbles to collect in the center of the tank while the heavier particles of oil seek the sides of the tank. When the pressure in the tank attains a certain value, valve 53 opens permitting oil to pass into conduit 54 from which a portion may pass to the bearings through branch 56.

The lower portion of tank 44 is now filled with oil of the required density and from this portion of the tank oil passes through conduit 46 to port 48 in cylinder 26. During the non-operating portions of the stroke of the piston 28, groove 49 therein registers with port 48 and if the fluid body needs replenishing oil flows into the piston 28 and through check valve 51 into conduit 22.

Any suitable means, such as a permanent leak of small size or an air vent valve such as shown in my prior application, Serial No. 126,297 filed July 31st, 1926, may if desired be mounted at the highest point in the chamber 20 to permit escape of air.

It will be apparent from the foregoing that I have provided effective means for removing air from the oil supplied the hydraulic system. The provision of the cylinder 26 and piston 28 separate from the crank case permits the use of materials having greater wear resisting properties and, the parts being small, they are very easily machined. This arrangement likewise possesses the advantage that the piston 28 is relatively free of side thrust as it does not contact with the cam.

Attention is also called to the fact that the

conduit 46 communicates with tank 44 slightly above the bottom thereof so that clogging of the conduit by collected sediment is avoided. If desired, the tank may be provided with a suitable plug 57 in its bottom to permit periodic draining.

The form of hydraulic column shown in Figures 1 and 2 is objectionable because of syphoning action. This objection does not apply to the construction illustrated in Figure 4, which is an adaptation of my separator to hydraulic mechanism of the type disclosed and claimed in my prior application Serial No. 126,297 filed July 31st, 1926. In this device oil from the separator 44 is supplied to chamber 60 provided with pressure relief valve 62 communicating with chamber 64. During the non-operating strokes of the tappet 66 oil flows from the reservoir 60 into the hydraulic chamber 68 and through that chamber to the highest point where a discharge valve 70 is provided establishing communication with the chamber 64 for the discharge of air in the manner described in my said application. Oil is returned from chamber 64 to the crank case in any suitable manner.

On the operating stroke of the tappet 66, plunger 72 displaces the liquid in chamber 68, causing plunger 74 to be depressed opening the valve indicated at 76.

I claim:

1. In an engine having one of the usual valves, a body of fluid, said valve being provided with means in operative relation with said body of fluid, means operated by said engine for displacing said fluid to impart movement to said valve, means for replenishing the fluid in said body, and means for removing air from the fluid supplied to said body, said last named means comprising an inertia separator.

2. In an engine having one of the usual valves, a body of fluid, said valve being provided with means in operative relation with said body of fluid, means operated by said engine for displacing said fluid to impart movement to said valve, means for replenishing the fluid in said body, and means for removing air from the fluid supplied to said body, said last named means comprising a combined centrifugal separator and settling tank.

3. In an engine having one of the usual valves, a body of fluid, said valve being provided with means in operative relation with said body of fluid, means operated by said engine for displacing said fluid to impart movement to said valve, means for replenishing the fluid in said body, and means for removing air from the fluid supplied to said body, said last named means comprising a centrifugal separator, and means for conducting the air containing portions of said fluid away from said separator.

4. The combination of an engine having a circulating lubricating system, hydraulic valve actuating mechanism, means for supplying said hydraulic mechanism with oil from said system, and means for removing
5 air from the oil supplied to said mechanism, and means for returning the air containing portions of said oil to the lubricating system.

5. The combination of an engine having a circulating lubricating system, hydraulic valve actuating mechanism, means for supplying said hydraulic mechanism with oil from said system, and means for removing air from the oil supplied to said mechanism, said last named means including a separating
10 chamber provided with a pressure relief valve and a conduit for the return of the air containing portions of the oil to the system.

In testimony whereof I affix my signature.
20 GEORGE E. A. HALLETT.
